UNITED STATES PATENT OFFICE

NATHAN E. NASH, OF WESTERLY, RHODE ISLAND.

IMPROVEMENT IN CUT-OFF VALVES AND GEARS.

Specification forming part of Letters Patent No. 154,802, dated September 8, 1874; application filed March 17, 1874.

To all whom it may concern:

Be it known that I, NATHAN E. NASH, of Westerly, in the county of Washington and State of Rhode Island, have invented certain Improvements in Cut-Off Valves for Steam-Engines, of which the following is a specification; and I do hereby declare that in the same is contained a full, clear, and exact description of my said invention, reference being had to the accompanying drawing, and to the letters of reference marked thereon.

My invention relates to certain devices, hereinafter described, for transmitting motion to the valves of steam-engines, by means of which devices the point at which the steam is cut off during the stroke of the piston is made variable, and governed by the action of the governor; to certain modifications in the said steam and exhaust valves fitting them to be operated by means of the aforementioned motive devices; and to other features looking to the adjustment of the steam-valves with reference to the "lead," made necessary by the varying amount of work to be performed or energy to be developed by the engine.

In the further description of my invention which follows, due reference must be had to the accompanying drawing, forming a part of this specification, and in which—

Figure 1 is a front elevation of an engine having my improvements thereupon; Fig. 2, an enlarged view of the exterior of the steam-cylinder with attachments; Fig. 3, a view of a detached portion of the invention; and Fig. 4, a view of the interior of the steam-chest, the bonnet or cover being removed.

A is the steam-cylinder, and B the steam-chest, provided with the bonnet or cover B'. D is a plate bolted steam-tight to the face of the cylinder, and in which are the steam-ports E E' and exhaust-ports F F'. The ports E E' and F F' in the plate D correspond with the steam and exhaust passages in the cylinder, being merely a continuation of them. G is a shaft, situate centrally of the steam-chest, and fastened at the inner end to the exhaust-valve H. To the outer end of the shaft G is fitted a rock-shaft, a, connected by means of the wrist-pin b to the eccentric rod c. The steam-valves are represented by I I', and in common with the exhaust-valve H bear against the

plate D. The valves I I' are fastened to shafts d d', which project through the cover of the chest, and have the arms e e' keyed to their outer ends. Motion from the rock-shaft a is communicated to the arms e e' by means of the curved bars f f', which are pivoted to a block, g, clamped to the rock-shaft a, and notched at their extended ends to engage projecting-pins h h' on the arms e e'. K is a rod, susceptible of a vertical motion only, which it receives from the engine-governor, which governor, as it forms no part of my invention, is not shown in the drawing. L L' are slotted rods, pivoted to the rod K, the pins securing them to the rod passing through the said slots, allowing the said slotted rods to have considerable longitudinal movement. The rods L L' are attached to the curved bars f f' near their notched ends. The shafts G, d, and d', where they pass through the steam-chest bonnet B', are packed, the said packing being held in position by the flange i.

The parts of my invention not yet alluded to will be duly considered as the operations of the different members constituting the machine are described.

The crank being at the center, as shown in Fig. 1, and the eccentric placed in such position with reference to the crank as to cause the shaft to revolve in the direction indicated by the arrow, steam from the steam-chest passes through the port E', which has been partially uncovered, into the cylinder, causing the piston to move and the shaft to revolve. The valve I' is now rapidly opened by means of the curved bar f', the movement in this direction continuing until the rock-shaft a and bar f have reached their extreme limit, when a retrograde motion of the rock-shaft and bar takes place, and the valve is forced back to its original position by the spring k'. After the crank has passed the other center, the valve I is opened, and the piston moves in an opposite direction.

The above description of the opening and closing of the valves is only applicable when the engine is working at "full stroke," or using steam from the steam-chest until the piston has reached the end of its stroke.

The steam is cut off by the action of the governor, raising the notches on the curved

bars $f f'$ from the pins $h h'$ on the arms $e e'$ by means of the rod K and slotted rods $L L'$, allowing the valves to be forced suddenly back and the ports closed by means of the springs $k k'$. It will be understood that the point of cutting off is regulated only by the vertical height of the rod K . The lead or opening given by the valves at the beginning of the stroke is regulated by the position of the adjustable block g , to which the curved bars $f f'$ are pivoted, and which may be elevated or depressed to diminish or increase the lead, as may be desired; but this adjustment may be accomplished automatically by attaching the movable block g by means of a system of levers and rods to the rod K , thereby increasing or diminishing the lead as the velocity of the piston is increased or diminished.

By reference to Fig. 4, it will be observed that the interior of the exhaust-valve is at all times in communication with the outlet-pipe M .

Having thus described my invention, what I claim as new, and desire to secure by Letters Patent of the United States, is—

1. The valves I , I' , and H , with their respect-

ive shafts, in combination with the bars $f f'$, rods $L L'$, and vertical rod K , rock-shaft a and arms $e e'$, with their pins $h h'$, the whole constituting a valve-gear, causing the point of cutting off the steam to be variable and consequent upon the movement of the governor transmitted through the medium of the said rod K , substantially as specified.

2. The vertically-adjustable block g , in combination with the rock-shaft a and bars $f f'$, as and for the purpose set forth.

3. The plate D , bolted to the face of the cylinder, and inclosed within the steam-chest, and having steam and exhaust ports corresponding with those in the cylinder and outlet-pipe M , in combination with the steam-valves $I I'$ and exhaust-valve H , operated by and upon their respective shafts, substantially as specified.

In testimony whereof I have hereunto subscribed my name.

NATHAN E. NASH.
